United States Patent Office.

JOSEPH F. UMPLEBY, OF ALBANY, NEW YORK.

Letters Patent No. 77,551, dated May 5, 1868.

IMPROVEMENT IN NEEDLE-BOOKS.

The Schedule referred to in these Letters Patent and making part of the same.

TO ALL WHOM IT MAY CONCERN:

Be it known that I, JOSEPH F. UMPLEBY, of Albany, in the county of Albany, and State of New York, have invented a new and improved Needle-Book; and I do hereby declare that the following is a full, clear, and exact description thereof, reference being had to the accompanying drawings, making a part of this specification, in which—

Figure 1 is a perspective view of the improved needle-book, showing it open.

Figure 2 is a perspective view, showing the book shut.

Figure 3 is a sectional view of the book.

Similar letters of reference indicate corresponding parts in the several figures.

This invention relates to a new and useful article of manufacture, consisting of a needle-book or case, which is adapted for receiving and preserving sewing-machine needles of various sizes, and which is provided with a needle-cushion and shield, for receiving and keeping the needles in place; also, a gauge, for accurately determining the sizes of the different needles required; and, also, certain spaces, having numbers and characters printed in them, indicating the different sizes of the needles used, and the "number" or size of the thread which the respective needles are designed to carry, as will be hereinafter described.

To enable others skilled in the art to understand my invention, I will describe its construction and operation.

The book or case consists of two covers, A A', connected together by a flexible back, *a*. This book or case may be made of binder's board, covered and finished in any suitable manner; and, if desirable, it may be furnished with a clasp, or other suitable fastening, for keeping the covers shut.

The cover A is lined with velvet or flannel, *b*, and has an oil-stone, *c*, fastened to it in a permanent manner, for the purpose of repairing the points of sewing-machine needles.

The cover A' is lined inside with strips, *f* *k*, of morocco, or other suitable material, between which is a strip, *e*, of velvet, or other suitable material, forming a cushion, for receiving the needles *d*, as shown. The outer edge of the flap or cover A' has a strip, *g*, of steel secured to it, in the edge of which straight notches, *h* *h*, are made, of various sizes, thus forming a needle-gauge, for accurately determining the sizes of the different needles required to be used.

The leather strips *f* *k* are marked off, so as to form seven, or more or less, spaces, for receiving the different-sized needles, as shown in fig. 1. The letters or figures printed upon the strip *k* will indicate the number, kind, and size of the needles in the spaces, corresponding to the said respective figures or letters; and the letters and figures printed upon the strip *f* will indicate the kind and size of the thread adapted for the several needles.

By trying the needles by the gauge-plate *g*, and then inserting them in their cushion *e*, beneath the shield *f*, these needles will not only be safely preserved for use, but the proper-sized needle may always be used for a given-sized thread.

If the needles are arranged in their proper places in the book or case, the letters and numbers upon the strips *f* *k* will, at a glance, indicate the size of each needle, and the size of the thread adapted for it.

The oil-stone *c* may be omitted; but I prefer to use this stone, and have it secured permanently inside of the book, thereby combining all the requisites in one article.

Having described my invention, what I claim as new, and desire to secure by Letters Patent, is—

1. The needle-book A A', constructed with cushion *K* *e* *f*, and with gauge-plate *g*, substantially as and for the purpose described.
2. The gauge-plate *g* *h*, applied to the needle-book, as described.
3. Providing a needle-book, constructed as shown and described, with the oil-stone *c*, which is arranged to bear against the cushion when the book is closed, as set forth.

JOSEPH F. UMPLEBY.
